APPARATUS FOR USE IN MAKING SHOES

Raymond G. Clinch, 12 Alpine St., Gorham, N.H.

Filed Apr. 21, 1958, Ser. No. 729,822

9 Claims. (Cl. 12—37)

This invention relates to apparatus for making shoes and especially to shoes having bottoms of rubber or plastic attached thereto by molding and fusion.

According to one method of making such shoes the upper is drawn on a last, the lasting margin is pulled inwardly over the bottom, for example by a draw string, sometimes called "string lasting" or by impaling the lasting margin on pins fixed in the bottom of the last and then the bottom of the lasted upper is brought into registration with an open top bottom mold, into which bottom forming material is placed, whereupon the bottom mold and last are heated to effect forming and fusion of the bottom to the upper.

The principal objects of this invention are to hold the upper sufficiently taut on the last so that during molding that portion of the upper material against which the bottom is being molded is not permitted to wrinkle or slide or in any way hinder passage of the molding compound, so that the molding compound will flow freely and fill the mold around the bottom and to hold the upper snugly on the last around the throat or foot opening so that it will not gape or sag during the molding and attaching of the bottom forming composition to the bottom. As herein illustrated, the last is mounted on a support which is movable relative to the bottom mold to bring the last into registration with the mold and there is means on the support for engagement with the upper adjacent the foot opening, constructed and arranged to apply tension to the upper heightwise of the bottom, in a direction to pull the upper taut and to hold the upper in close contact with the sides of the last adjacent the foot opening. The aforesaid means is in the form of tension means, of which there are two, having means at one end for attachment to the upper at opposite sides. The other ends are connected to levers pivotally mounted on the support and there are abutments on the support near the ends of the levers opposite the ends to which the tension devices are attached, against which the levers may be placed to hold them in positions to stress the tension devices relative to the ends attached to the upper. The ends for engagement with the upper are provided with hooks or anchor plates adapted to be engaged with the eyelets at opposite sides of the foot opening. The apparatus preferably has diametrically opposed lasts mounted for rotation about a given axis so that while one is in an operative position the other is in a loading position and the levers are so arranged that the tension devices may be transferred from a position in which they hold an upper on a last while the latter is in operative position until fusion is nearly complete, to a position for holding an upper mounted on the last at the loading position, preparatory to moving this last into operative position for the bottom attaching operation.

The invention will now be described in greater detail with reference to the accompanying drawings wherein:

Fig. 1 is a side elevation of the upper part of a bottom attaching machine such as shown in pending application Serial No. 404,608, filed January 18, 1954, by Henry

2

Hardy, and now Patent No. 2,878,523, issued March 24, 1959.

Fig. 2 is a fragmentary elevation to larger scale showing the tension producing means;

Fig. 3 is a fragmentary plan view looking down at the top of Fig. 2, with the upper last and its supporting means omitted;

Fig. 4 is a plan view of a hook for connecting the tension producing means to an eyelet in the upper;

Fig. 5 is a plan view of an anchor plate for connecting an end of the tension means to the eyelet in the upper;

Fig. 6 is a section taken on the line 6—6 of Fig. 5;

Fig. 7 is an elevation of a spring clamped jaw; and

Fig. 8 is an end view of the clamp shown in Fig. 7.

Referring to the drawings, the machine has a base 10 which supports on posts 12 bearings 14, in which is mounted a horizontal shaft 16 adapted to be turned about its horizontal axis, as disclosed in the aforementioned pending application. The shaft has fastened to it at diametrically opposed points bolts 18, which extend radially from the shaft 16, on which are mounted brackets 20. A last 22 is fastened to each bracket and by turning the shaft 16 each last in turn may be moved from the upper position shown in Fig. 1, to the lower position in registration with a bottom mold 24 resting on the base 10. The upper position is the loading position at which an upper is placed on the last and the lower position is a bottom attaching position in which a bottom or bottom forming composition is molded and fused to the bottom of the upper.

According to one mode of applying the upper to the last the lasting margin is drawn inwardly over the bottom by a draw string. Since the upper is usually a woven material and has little body this type of lasting does not hold the upper snug and there is a tendency for that portion of the margin pulled in over the shoulder to wrinkle and that part around the foot opening to gape. Wrinkling at the bottom hinders the free flow of the molding compound and gaping at the foot opening results in a poor looking shoe. To reduce this it is not uncommon to secure pins in the wall of the last at the neck and in the bottom adjacent the shoulder and to impale the upper around the foot opening and the lasting margin, particularly around the shank, on these pins to hold the upper taut and smooth, but such means has not been wholly successful.

According to this invention tension is maintained in an upper U, which has been assembled on the last 22, for example by string lasting, by tension producing means 26, of which there are two, one at each side of the shaft 16, so that both sides of the upper may be placed under tension as shown in Figs. 1 and 2. Each means comprises a plurality of spring elements or strands 28 having hooks 30 at their extremities for engagement with the eyelet openings 32 at one side of the upper U. The strands are connected to one screw 34 of a turnbuckle 36. The other screw 38 of the turnbuckle is connected by a spring 40 to one end of a lever 42 pivotally mounted on a stud 44, extending laterally from that side of the shaft 16. The lever is yieldably held against a boss 46 on the stud by a spring 48 lodged behind the head of the stud. An abutment pin 50, projecting from the shaft 16 into an aperture 42a in the lever 42, provides means for holding the lever arm 42 in such a position that the tension means applies tension to the upper heightwise of the bottom of the last in a direction to pull it onto the last. Alternatively, the aperture 42a in the lever 42 may be omitted, the lever 42 then engaging the side of the abutment pin 50 which is nearest the upper being held under tension. To disengage the tension means from the upper the arm 42 is pulled outwardly to release engagement of the abutment pin 50 and turned in a counterclockwise direction,

as shown in Fig. 2, to relieve the tension and hence permit disengagement of the hooks from the eyes.

Instead of using hooks 30, anchor plates 52, such as shown in Figs. 5 and 6 may be employed. These plates are connected by strands 54 to the screw 34, are adapted to lie between the wall of the last and the inside of the upper adjacent the eyelet holes and have pins 56 projecting therefrom for engagement with the eyelet holes.

Alternatively, spring clamps 58 may be employed such as shown in Figs. 7 and 8, the jaws of which may be engaged with the upper edge of the upper at appropriate places to hold the upper smoothly.

As has been pointed out above, the apparatus is provided with two lasts so that while one last is in registration with the bottom mold for attachment of a bottom member thereto, the other is in a position for mounting of an upper in preparation for attachment of the bottom thereto. The tension producing apparatus is accordingly designed so that the tension can be maintained in the upper, that is, in bottom attaching position during that part of the fusion when the bottom forming compound is flowing about the bottom and until fusion is nearly completed, and then may be disconnected and transferred to the upper at the loading position just before the completed shoe is finished, and connected to the upper on the last at the loading position to make it ready for the bottom attaching operation. This effects a saving in time and avoids a duplication of tensioning means. The transfer of the tensioning means is illustrated clearly in Fig. 1, from the full line position in which it is holding the upper in bottom attaching position under tension to the dotted line position in which it is holding the assembled upper on the last at the loading position. All that is required is that the tension producing means be disconnected from the upper on the lower last, and the means be swung upwardly and connected to the upper on the upper last. The arm 42 is temporarily released from the position in which it engages the abutment pin 50 during the transfer of the tension producing means thereby releasing tension in the spring elements 28 and 40 for facilitating said transfer.

It is evident from the foregoing that a very simple tension producing means is thus provided which may be adjusted to produce various degrees of tension, is adaptable to different size shoes and eliminates the necessity of providing the last with special attaching pins.

It should be understood that the present disclosure is for the purpose of illustration only and that this invention includes all modifications and equivalents which fall within the scope of the appended claims.

I claim:

1. In combination with a machine for attaching a bottom to an upper on a last, a pair of lasts each being adapted to support an upper with its lower margin secured inwardly of the shoulder at the bottom, means mounting the lasts for successive movement to a position to have a bottom attached first to one and then to the other upper supported on said lasts, and tension means carried by the last-named means for applying a pull to said one upper heightwise of the bottom in a direction to hold the upper taut on the last, said tension means being transferable from said one upper to said other upper for successively holding the upper with which it is engaged taut on its last during attaching of a bottom thereto.

2. Apparatus according to claim 1, wherein the tension means includes a plurality of springs having individual hooks arranged to be engaged with the eyelet holes in the upper.

3. Apparatus according to claim 1, wherein the tension means includes, at one end, anchoring plates adapted to lie between the last and the upper next to the eyelets and

pins fastened thereto which are adapted to project through the eyelets from the inside.

4. Apparatus according to claim 1, wherein the tension means includes, at one end, spring clamps, the jaws of which are adapted to be engaged with the upper edge of the upper.

5. In combination with a machine for attaching a bottom to an upper on a last, a pair of lasts each of which is adapted to support an upper with its lower margin secured inwardly of the shoulder at the bottom, a support mounting the lasts for successive movement to a position to have a bottom attached first to one and then to the other upper supported on said lasts, and contractile means connected at one end to said one upper and at the other ends to the support under tension which exert a pull on the upper heightwise of the bottom in a direction to hold the upper taut on the last, the said one end of said contractile means being transferable from one upper to said other upper for successively holding an upper taut on its last during attachment of a bottom thereto.

6. In combination with a machine for attaching a bottom to an upper on a last, a last for supporting the upper with its lower margin secured inwardly of the shoulder at the bottom, a support mounting the last for movement to a position to have a bottom attached thereto, spring means connected at one end to the upper, levers on the support to which the other ends of the spring means are attached and abutments on the support against which the levers may be placed to hold the spring means under tension.

7. In combination with a machine for attaching a bottom to an upper on a last, a last for supporting the upper with the lower margin secured inwardly of the shoulder at the bottom, a support mounting the last for movement to a position to have the bottom attached thereto, spring means connected at one end to the upper, a pair of levers pivotally mounted on the support to one end of which the other ends of the spring means are attached, abutments on the support at the other side of the pivots engaged by the other end of the levers for holding the spring means under tension, and said levers being laterally displaceable to disengage them from the abutments.

8. In combination with a machine for attaching a bottom to an upper on a last, a support mounting a pair of lasts at diametrically opposite positions for movement of one into operative position and the other to a loading position, a pair of levers pivotally mounted on the support midway between the lasts, spring means connected at one end to one end of each lever, the opposite end of each spring means being adapted to be connected to the upper on either one of the lasts, and abutments on the support with which the other end of each lever may be engaged to hold the spring means under tension.

9. In combination with a machine for attaching bottoms to uppers pulled on lasts, a support mounting a pair of lasts at diametrically opposite positions for movement about an axis midway between them to bring one last into an operative position and the other into a loading position, a pair of levers on the support substantially at the axis of rotation at opposite sides thereof, and tension producing means mounted on the support at both sides thereof for applying tension to the upper at both sides, said tension producing means being connected at one end to the levers and their opposite ends being translatable from the upper on one last to the upper on the other last.
